STRAPLESS BREAST SUPPORT OR SIMILAR ARTICLE

Harry Jay Dubner, New York, N. Y.

Application May 31, 1951, Serial No. 15,359

Term of patent 14 years

(Cl. D20—4)

To all whom it may concern:

Be it known that I, Harry Jay Dubner, a citizen of the United States and resident of New York, in the county and State of New York, have invented a new, original, and ornamental Design for a Strapless Breast Support or Similar Article, of which the following is a specification, reference being had to the accompanying drawing, forming a part thereof, and of which

Fig. 1 is a perspective view of a strapless breast support, showing my new design appearing as worn, the wearer's body being indicated in dotted lines, for convenience of illustration.

Fig. 2 is a side elevational view thereof;

Fig. 3 is a front elevational view thereof, while

Fig. 4 is a plan view of the strapless breast support showing same in spread-out condition.

I claim:

The ornamental design for a strapless breast support or similar article, as shown and described.
HARRY JAY DUBNER.
